UNITED STATES PATENT OFFICE.

WOLFGANG TURNWALD, OF SYRACUSE, NEW YORK, ASSIGNOR TO STUMPF UNA-FLOW ENGINE COMPANY, A CORPORATION OF NEW YORK.

AUTOMATIC EXHAUST-VALVE.

1,285,475.

Specification of Letters Patent. Patented Nov. 19, 1918.

Application filed December 15, 1915. Serial No. 66,905.

To all whom it may concern:

Be it known that I, WOLFGANG TURNWALD, a subject of the Emperor of Austria, residing at Syracuse, in the county of Onondaga, State of New York, have invented a new and useful Improvement in Automatic Exhaust-Valves, of which the following is a specification.

My invention relates to improvements in automatic exhaust valves adapted for use in connection with double acting steam cylinders. The object of the invention is to provide automatic means operated by steam pressure in the cylinder to open and close these valves when the engine is operating normally non-condensing. The invention also comprises means whereby the engine may run condensing with said exhaust valves both closed but which will automatically open if the vacuum is broken.

Referring to the drawings which illustrate merely by way of example suitable means for the embodiment of my invention—

Figure 1 is a longitudinal section of a una-flow steam cylinder showing my valve mechanism.

Fig. 2 is a detail showing mechanism for maintaining both valves closed when the engine is running condensing.

Fig. 3 is a longitudinal vertical section showing my valve mechanism in connection with a counterflow cylinder.

Fig. 4 is a longitudinal vertical section showing a modification, in which the valves are puppet valves, each operated separately by its own steam piston.

Similar numerals refer to similar parts throughout the several views.

In Fig. 1, I show the invention as applied to a una-flow steam cylinder 5, which is provided with the main exhaust ports 6 delivering to an exhaust belt 7. The exhaust ports 6 are adapted to be overrun by the piston 8, indicated in dotted lines, which maintains said ports closed until the end of the working stroke, when they are uncovered for the exhaust of the expanded steam. Upon the next return stroke the piston covers the ports 6 and traps the balance of the steam which has not been exhausted. When the engine is running normally non-condensing, steam is discharged through the auxiliary exhaust ports 9 and 10 until the piston 8 covers said ports and traps and compresses the balance of the undischarged steam.

These exhaust ports 9 and 10 are controlled by the pistons 12 and 13 operating in the cylinders 14 and 15 respectively. These pistons 12 and 13 are provided with piston extensions 16 and 17 respectively which operate in cylinders 18 and 19. The ends of cylinder 5 are connected by any suitable means, such as pipes 33, with the spaces 34 in the ends or heads of the cylinders 18 and 19.

The driving pistons 16 and 17, as shown, are of less diameter than the piston valves 12 and 13, thereby forming annular spaces 21 which can be utilized for dash pots. Both the pistons 12 and 13 and the extensions 16 and 17 may be if desired, provided with piston rings, as shown, or other suitable means to prevent leakage. Communicating with the annular spaces or dash pots 21 are the channels 22 controlled by the needle valves 23.

The operation is as follows:—

As already stated, at the end of a power stroke the piston 8 uncovers the exhaust ports 6 for the exhaust of the expanded steam. Upon the return stroke the piston 8 covers the exhaust ports 6 and traps the balance of the steam in the cylinder and forces the steam through, for example, port 9 into exhaust belt 7 until the piston 8 covers said port 9, whereupon the balance of the steam is trapped between the piston head and the end of the cylinder and compressed. As the compression increases, pressure is communicated to the space 34 of cylinder 18 and, after the main exhaust ports are opened, forces pistons 12 and 16 to the left thereby closing port 9 and simultaneously moving pistons 13 and 17 to the left thereby opening port 10. The space between the shoulder 20 and inclined surface of the cylinder wall forms a dash pot for eliminating any impact between said surfaces. The proper adjustment of needle valve 23 secures the desired regulation of dash pot efficiency. Upon the return stroke of piston 8 a portion of the trapped steam is now discharged through port 10 until the port is closed by piston 8 and the balance of the steam being entrapped and compressed causes the actuation of the piston mechanism to the right, thus repeating the cycle.

For the purpose of providing mechanism which will operate when the engine is running non-condensing, and automatically

close both ports 9 and 10 and maintain them closed when running condensing, I show in Fig. 2, valve pistons 12 and 13 pivotally connected to the rods 25 and 26 which are jointed or pivotally connected together at 27 and also connected at said pivot 27 with the connecting rod 28 which in turn is pivotally connected at 29 with the piston 30 operating in the cylinder 31 and normally controlled by the spring 32 to maintain the rods 25 and 26 in alinement. The space in cylinder 31 beneath the piston 30 is connected to the condenser not shown.

Operation: When the engine is running non-condensing the spring 32 will maintain the piston 30 in the elevated position against the stops 33 which will maintain the connecting rods 25 and 26 in substantial alinement, and will permit the same to move from the right to the left, and vice versa, with very slight deflection from said straight alinement as indicated by the arc 47, which is the arc of the circle of which 29 is the center. When, however, the engine is running condensing, the cylinder 31 being connected by the pipe 35 with the condenser, a reduced pressure is created in cylinder 31 beneath piston 30, which will draw the piston downwardly, thus maintaining the pistons 12 and 13 against the stops 36, in the closed position, during such operation of the engine.

In Fig. 3, I show the invention applied to a counterflow steam cylinder, thus obviating the necessity of outside valve mechanism for operating the exhaust valves. In this case the admission of live steam into the cylinder end at the commencement of the stroke will operate the piston valves to close the exhaust port at the same end of the cylinder and to open the exhaust port at the other end of the cylinder.

It will be obvious that the invention need not be confined to the use of piston valves, since any form of valve and valve control may be employed which may read within the scope of the claims.

In Fig. 4, I show the exhaust ports 9 and 10 controlled by the puppet valves 37 and 38, the spindles of which are connected with the pistons 39 and 40 operating in the cylinders 41 and 42. The bottoms of these cylinders are connected by the pipes 43 and 44 with the opposite ends of the cylinder 5 and the portion of one cylinder below piston 40 is connected with the top of the other cylinder above piston 39 by the pipe 45 while the bottom of cylinder 41 is connected with the top of cylinder 42 by the pipe 46.

The operation is as follows:—Pressure at the right hand end of the cylinder 5 is communicated through pipe 43 to the bottom of cylinder 41 beneath the piston 39 to cause the closing of valve 37 and pressure

at the same time is communicated through pipe 46 to the upper part of cylinder 42 above piston 40 to actuate valve 38 to open port 10. In a similar way pressure at the left hand end of cylinder 5 closes port 10 and opens port 9.

What I claim is:—

1. In combination with a double acting steam cylinder provided with exhaust ports between the middle part and the ends thereof, piston valves for controlling said ports, actuating pistons therefor operated by the compression pressure of the cylinder, and mechanism controlled by pressure conditions of the condenser for the further control of said pistons.

2. The combination with a double acting steam cylinder provided with exhaust ports between the middle part and the ends thereof, piston valves for controlling said ports, actuating pistons therefor operated by the compression pressure of the cylinder, a cylinder connected with a condenser, a piston operating therein, and means for establishing operative relationship between said last mentioned piston and the piston valves.

3. In combination with a double acting steam cylinder provided with exhaust ports between the middle part and the ends thereof, piston valves for controlling said ports, actuating pistons therefor operated by the compression pressure of the cylinder, jointed rods connecting said valve pistons, a cylinder connected with a condenser, a piston operating therein and means connecting said last mentioned piston with the jointed rods.

4. In combination with a double acting steam cylinder provided with exhaust ports between the middle part and the ends thereof, piston valves for controlling said ports, actuating pistons therefor operated by the compression pressure of the cylinder, jointed rods connecting said valve pistons, a cylinder connected with a condenser, a piston operating therein, means connecting said last mentioned piston with the jointed rods, a spring for controlling the last mentioned piston for normally keeping the jointed rods in alinement, said piston adapted to respond to pressure conditions of the condenser to compress the spring, to pull the rods out of alinement and to move the piston valves into closed position.

5. In combination with a double acting steam cylinder provided with exhaust ports between the middle part and the ends thereof, piston valves for controlling said ports, actuating pistons therefor, jointed rods connecting said valve pistons and a condenser controlled mechanism for normally holding said rods in alinement to secure simultaneous movement of said valve pistons in the same direction.

6. In combination with a double acting

steam cylinder provided with exhaust ports between the middle part and the ends thereof, piston valves for controlling said ports, actuating pistons therefor, and jointed rods connecting said valve pistons and a condenser controlled mechanism for normally holding said rods in alinement to secure simultaneous movement of said valve pistons in the same direction, but adapted 5 when the engine is running condensing to move said rods out of alinement to cause the simultaneous movement of the valve pistons in opposite directions.

7. In combination with a double acting steam cylinder, an auxiliary exhaust port near each end thereof, valves for closing said exhaust ports and means operated by the pressure of the steam in the cylinder after the piston has overridden one of said 10

ports for closing said port and opening the other port, and means connected with a condenser for automatically moving both exhaust valves into closed position.

8. In a double acting steam cylinder provided with auxiliary exhaust ports near its ends, valves for controlling said exhaust ports and means operated by the pressure of the steam in the cylinder after the piston has overridden an exhaust port for actuating said valves to close the last mentioned port and to open the other port, and means connected with a condenser for automatically maintaining said auxiliary exhaust ports closed.

WOLFGANG TURNWALD.
